UNITED STATES PATENT OFFICE.

LAWRENCE W. CASE, OF HIGHLAND PARK, CONNECTICUT.

PAPER-POLISHING MACHINE.

SPECIFICATION forming part of Letters Patent No. 734,666, dated July 28, 1903.

Application filed November 21, 1902. Serial No. 132,251. (No model.)

To all whom it may concern:

Be it known that I, LAWRENCE W. CASE, a citizen of the United States, residing at Highland Park, in the county of Hartford and State of Connecticut, have invented certain new and useful Improvements in Paper-Polishing Machines, of which the following is a specification.

This invention relates to a machine for polishing paper by means of the friction of a moving glassing-stone that is forced against the surface of the paper with suitable pressure.

The object is to provide a simple machine of this nature which will polish a continuous web of paper of any width or thickness rapidly, uniformly, and efficiently.

The embodiment of the invention that is illustrated has an adjustable bed, glassing-stones that are adapted to be revolved upon the upper surface of the bed, and means for advancing a web of paper on the bed beneath the stones.

Figure 1 of the accompanying drawings shows a front elevation of one of these machines. Fig. 2 shows a side elevation with the roll of paper and the paper-feeding mechanism omitted; and Fig. 3 is a plan, on slightly smaller scale, of the machine.

The bed 1, which is an annular metal plate, is supported upon posts 2. The upper ends of the posts extend into sockets in the under side of the bed and the lower ends of the posts are threaded and fit threaded sockets in the upper face of the base 3. When the posts are rotated, the bed is raised or lowered according to the direction of the rotation of the posts. Each post bears a pinion 4 and one bears a hand-wheel 5. Supported by an arbor between the base and the bed is a large gear 6, the teeth of which mesh with the teeth of the pinions on the posts. By means of the gear and pinions all of the posts are rotated simultaneously and move the bed up or down uniformly when the hand-wheel is turned.

A frame 7, that rises from the base, has bearings holding a vertical shaft 8. On this shaft, the axis of which is in line with the axis of the bed and the large gear, is a driving-pulley 9, that is adapted to be belted to the source of power. Projecting radially

from a hub on the lower end of the shaft just above the bed are a number of arms 10. The machine shown has four of these arms; but any suitable number may be used. In one side of the outer end of each arm there is a T-shaped slot 11, and held to the side of each arm by a nut that moves in the slot is a block 12. Held to each of these blocks by a clamp-plate 13 is a glassing-stone 14, which may be made of flint, agate, glass, or other hard substance. When the nuts are loosened, the blocks are movable along the arms for the purpose of adjusting the stones.

At one side of the machine, supported by a suitable frame, are two feed-rollers 15, that have intermeshing gears 16 at one end of their shafts, so as to rotate together. The pressure of these rollers against each other is regulated by hand-screws 17. At one end of one feed-roller shaft is a worm-wheel 18, meshing with a worm 19 on a vertical shaft 20, that has a pulley 21, that is connected with a pulley 22 on the vertical shaft 8 by a belt 23.

An idler-roller 24 and a tension-roller 25 are supported by the frame near the feed-rollers.

The paper 26, which may be press-board or any other stock that it is desired to polish by friction, is rolled upon an arbor 27, that is laid across a frame at the side of the machine opposite the feed-rollers. An idler-roller 28 is laid across the frame at this side adjacent to the roll of paper.

The paper is led from the roll over the idler-roller, across the top of the bed beneath the glassing-stones, and over the idler-roller at the opposite side, then under the tension-roller and between the feed-rollers. The paper is drawn slowly across the bed by this mechanism when the machine is in operation, and at the same time the glassing-stones are caused to revolve about the axis of the bed, so as to rub the entire surface of the paper. These stones are adjusted along the arms, so that each will form a track for itself—that is, all are not adjusted equal distances from the axis of revolution. As the stones are revolved upon the upper surface of the paper the hand-wheel is turned to lift the bed and determine the pressure of the stones upon the paper. The stones make complete revolutions and the paper is advanced slowly, so the entire

surface of the paper is subjected to the rubbing of the stones many times.

This invention provides a machine having glassing-stones, which revolve smoothly and bear heavily upon the paper to be polished. This effective machine is simple to build, easy to operate, and quick to adjust.

I claim as my invention—

1. A machine for polishing paper having a bed, a shaft supported over the bed, arms rotatably supported by the shaft over the bed, glassing-stones attached to the arms, and mechanism for feeding paper between the bed and the stones, substantially as specified.

15 2. A machine for polishing paper having a bed, means for raising and lowering the bed, arms rotatably supported above the bed, glassing-stones attached to the arms, and means for feeding paper between the bed and the stones, substantially as specified.

3. A machine for polishing paper having a bed supported by threaded posts, pinions and a gear for rotating the posts simultaneously, arms rotatably supported above the bed, 25 glassing-stones attached to the arms, and means for feeding paper between the bed and the stones, substantially as specified.

4. A machine for polishing paper having a bed, a shaft supported over the bed, arms rotatably supported by the shaft over the bed, 30 glassing-stones adjustable radially of the shaft along the arms, and mechanism for feeding paper between the bed and the stones, substantially as specified.

5. A machine for polishing paper having a 35 bed, means for raising and lowering the bed, a shaft supported over the bed, arms rotatably supported by the shaft over the bed, glassing-stones adjustable radially of the shaft along the arms, and mechanism for feeding 40 paper between the bed and the stones, substantially as specified.

6. A machine for polishing paper having a bed, a shaft supported over the bed, a glassing-stone suspended above and adjacent to 45 the face of the bed and adapted to be revolved by the rotation of the shaft, mechanism for rotating the shaft, and mechanism for feeding paper between the bed and the stone, substantially as specified.

LAWRENCE W. CASE.
